UNITED STATES PATENT OFFICE.

RICHARD B. OWEN, OF WASHINGTON, DISTRICT OF COLUMBIA.

INTERNAL-COMBUSTION ENGINE.

1,297,897.

Specification of Letters Patent. Patented Mar. 18, 1919.

Application filed October 8, 1915. Serial No. 54,842.

To all whom it may concern:

Be it known that I, RICHARD B. OWEN, a citizen of the United States, residing at Washington, in the District of Columbia, 5 have invented certain new and useful Improvements in Internal-Combustion Engines, of which the following is a specification.

This invention relates to an improvement 10 in internal combustion engines and more particularly to a fuel or gasoline tank for use with the same, it being an object of my invention to construct and mount the tank in a manner that the fly wheel is received in a recess provided therein.

A further object is to provide a cover to fit over the recess and entirely close in the fly wheel, together with releasable means to hold the cover in the closed relation and 20 arranged to permit opening of the same to allow manual movement of the fly wheel to start the engine.

A still further object is to provide a handle mounted on the fly wheel at a point to 25 be accessible in the starting operation and arranged to move to a position that the cover may be closed subsequent to the starting of the engine.

This invention relates to still other novel 30 features of construction and combination of parts which will be hereinafter more particularly described in connection with the accompanying drawings and pointed out in the appended claims.

35 In the drawings:

Figure 1 is a top plan view of one embodiment of my invention.

Fig. 2 is a transverse vertical sectional view taken on the line 2—2 of Fig. 1.

40 Fig. 3 is a fragmentary sectional view through a portion of the rim of the fly wheel to better illustrate the mounting of the starting handle.

In the present instance the internal combustion engine is illustrated as having the 45 crank shaft vertically disposed, and thus the crank case 1 has the crank shaft bearings 2 extending upwardly and downwardly therefrom, the crank shaft 3 being journaled in these bearings to operate in the usual manner and the engine structure made of standard construction.

A fuel or gasoline tank 4 constructed of 50 sheet metal or other suitable material is made preferably substantially U-shaped as best illustrated in Fig. 1, and this tank is

disposed around the bearing 2 of the engine and is supported by any form of suitable bracket such as that shown at 5 in Fig. 2. This tank has a filler opening which 60 is closed by a filler cap 6, and that portion of the upper face of the tank adjacent the bearing 2 is shaped to form the recess 7, this recess being made preferably substantially circular in plan as is illustrated in 65 Fig. 1, and the fly wheel 8 is mounted on the crank shaft 3 to be inclosed at its sides by the upstanding portion of the tank.

In the open portion of the U-shaped tank a magneto 9 is fitted and this magneto may 70 be driven through the gear 10 on the shaft thereof and the gear 11 mounted on the crank shaft 3. It will be understood that where a magneto is to be installed it is preferable that the tank 4 be made of the U- 75 shaped form, but where it is not desired to install the magneto, the tank may be made substantially continuous around the crank shaft and where this is done it will be understood that the recess 7 will be continued in this 80 annular extent entirely around the shaft also.

A cover 12, which is preferably circular and of a larger diameter than the recess, is hinged or pivoted by a pin 13 on the upper 85 face of the tank and this cover is adapted to be swung to a position to fit over and close the recessed portion.

A handle 14 is provided on the cover 12 to facilitate movement thereof, and a suitable 90 catch 15 is provided on the tank to engage with a portion of the cover to releasably secure the same in the closed relation. In some instances it may be found advisable to secure the fly wheel upon the crank shaft by 95 the use of a nut 16, and under such circumstances it will be found necessary to provide the cover 12 with a boss 17 to receive the nut during the working of the engine and when the cover is closed.

100 As the cover 12, when closed, fits closely adjacent the outer face of the fly wheel, it is desirable that a starting handle be provided on the fly wheel which will move to a position subsequent to the starting of the engine that no projection will be offered from the face of the wheel.

105 As is better illustrated in Fig. 3, the rim of the fly wheel 8 is recessed at 18 and a handle 19 is mounted on a pivot pin 20 which 110 extends substantially radially in the fly wheel, and by thus arranging the parts the

handle 19 may be raised from the recess to extend from the wheel to permit starting of the engine and when the fly wheel has attained any considerable momentum, will fall back again into the recess so that it is flush with or below the outer surface of the fly wheel and the cover may be closed.

In starting the engine, the handle 19 is raised to extend from the fly wheel in a relation substantially parallel with the line of extent of the crank shaft, this handle is grasped and the desired movement to start the engine is given to the fly wheel, then as the engine is started, the handle is released from the grasp and again automatically falls into the recess after which the cover 12 may be swung around its hinged connection at 13 to a closed position and is releasably held in the closed relation by the catch 15.

While I have herein shown and described but one specific form of my invention, it will be understood that the cover might take various other forms and be fitted in divers other ways, and also that the remaining parts of the structure might be varied without departing from the spirit and scope of my invention and hence I do not wish to be limited except for such limitations as may appear in the claims.

I claim:—

1. In combination with an internal combustion engine having the fly wheel thereof adapted for use in starting the engine, a fuel tank mounted adjacent the fly wheel and shaped to cover the same at the rim edge thereof and to leave the outer face exposed for manual manipulation in the starting of the engine, and a cover hingedly mounted on the fuel tank to be closed over the fly wheel.

2. In combination with an internal combustion engine having the fly wheel thereof arranged to be manually moved to start the engine, a fuel tank having a recess therein mounted on the supporting parts of the engine to have the fly wheel received in the recess thereof and to thus cover the fly wheel at the rim edge, and a cover mounted on the fuel tank to be closed over the fly wheel subsequent to the starting operation.

3. In combination with an internal combustion engine having the fly wheel thereof mounted on one end of the engine shaft, a fuel tank having a recess formed therein of substantially the shape of the fly wheel and which fuel tank is mounted around the engine shaft in such relation that the fly wheel is received in the recess, and a cover pivotally mounted on the fuel tank at one side of the recess and shaped to be swung to cover over the recess and consequently cover the fly wheel.

4. In combination with an internal combustion engine having the fly wheel thereof mounted on one end of the engine shaft, a

fuel tank having a recess formed therein of substantially the shape of the fly wheel and which fuel tank is mounted around the engine shaft in such relation that the fly wheel is received in the recess, a cover pivotally mounted on the fuel tank at one side of the recess and shaped to be swung to cover over the recess and consequently cover the fly wheel, and means carried by the fuel tank on that side opposite to which the cover is pivoted, adapted to engage with the cover and hold the same in the closed position.

5. The combination of an internal combustion engine having a fly wheel fitted at one end of the crank shaft, and a fuel tank shaped to be received around the crank shaft and provided with a recess to have the fly wheel fitted therein.

6. In combination with an internal combustion engine having a fly wheel mounted on one end of the shaft thereof and thus disposed away from the main parts of the engine, a fuel tank made open in its center to be received around the engine shaft and having a recess in one side thereof to receive the fly wheel and in which the fly wheel is inclosed with its outer side substantially flush with the face of the fuel tank.

7. The combination with an internal combustion engine of a fuel tank fitted around the crank shaft of the engine and provided with a recessed portion to receive the fly wheel of the engine, and a starting handle mounted on said fly wheel to project from the recessed portion to permit manual movement of the wheel during starting of the engine.

8. The combination with an internal combustion engine of a fuel tank fitted around the crank shaft of the engine and provided with a recessed portion to receive the fly wheel of the engine, and a starting handle movably mounted on said fly wheel to project from the recess during the starting of the engine and arranged to automatically move to a position entirely within the confines of the recessed portion after the engine is started.

9. The combination with an internal combustion engine of a fuel tank fitted around the crank shaft of the engine and provided with a recessed portion to receive the fly wheel of the engine, and a starting handle movably mounted on said fly wheel to project from the recess during the starting of the engine and arranged to automatically move to a position entirely within the confines of the recessed portion after the engine is started, and a cover to close said recessed portion.

10. The combination with an internal combustion engine having the fly wheel constructed to be manually moved to start the same, a starting handle movably fitted to said fly wheel to project therefrom during

the starting operation and to move from the position of projection when the engine is started, and a cover to fit over the fly wheel when the handle is moved from the position of projection.

11. The combination with an internal combustion engine having the fly wheel constructed to be manually moved to start the same, a starting handle movably fitted to said fly wheel to project therefrom during the starting operation and to move from the position of projection when the engine is started, a cover to fit over the fly wheel when the handle is moved from the position of projection, and means to hold the cover in the closed position.

12. In combination with an internal combustion engine having a fly wheel mounted on one end of the shaft thereof and thus disposed away from the main parts of the engine, a fuel tank made open in its center to be received around the engine shaft and having a recess in one side thereof to receive the fly wheel and in which the fly wheel is inclosed with its outer side substantially flush with the face of the fuel tank, a cover pivotally mounted at one side of the recess

and upon the fuel tank to be swung over to close the recess and cover the fly wheel, and means carried by the tank to engage with the cover and hold the same in the closed position.

13. The combination with an internal combustion engine of a substantially U-shaped tank fitted around the crank shaft thereof and provided with a recessed portion formed adjacent the crank shaft to receive the fly wheel and a cover to be received over the recessed portion to inclose the fly wheel.

14. The combination with an internal combustion engine of a substantially U-shaped tank fitted around the crank shaft thereof and provided with a recessed portion formed adjacent the crank shaft to receive the fly wheel, a cover to be received over the recessed portion to inclose the fly wheel, and means to hold the cover in a closed relation.

In testimony whereof I hereby affix my signature in presence of two witnesses.

RICHARD B. OWEN.
